FIREBRICK WALL CONSTRUCTION

William A. Waite, Providence, R. I.

Application July 18, 1938, Serial No. 219,719

12 Claims. (Cl. 72—102)

My present invention relates to furnace wall constructions, and has particular reference to a novel arrangement of brick therefor.

It is the principal object of my invention to provide a furnace wall construction designed to overcome mechanical failure due to expansion and contraction strains on the inner lining of the wall.

It is another object of my invention to provide a wall construction which resists the tendency of the inner lining brick courses to bend and buckle inwardly and to pull away from the cooler outer portion of the wall.

A further object of my invention is to utilize the weight of the inner lining to press the inner lining courses toward the outer portion.

Still another object is to progressively transfer the weight of the furnace wall from the inner lining to the cooler outer portion.

An additional object of my invention is to provide simple and effective provision for the uneven vertical expansion and contraction that normally occurs in a furnace wall.

A further object is to provide a wall construction comprising a plurality of separate wall panels on the furnace face, each of which may independently expand and contract and may be removed and replaced with minimum disturbance to the adjacent panels and the outer supporting wall.

With the above and other objects and advantageous features in view, my invention consists of a novel arrangement of parts more fully disclosed in the detailed description following, in conjunction with the accompanying drawings, and more specifically defined in the appended claims.

In the drawings:

Fig. 1 is an elevation of a furnace wall embodying the novel invention;

Fig. 2 is a vertical section thereof;

Fig. 3 is a vertical section of a modified construction, designed for air cooling;

Fig. 4a is a plan view of a standard header used for the outer portion, Fig. 4b being a side elevation thereof;

Fig. 5a is a plan view of a modified form of header used for the inner lining, and Fig. 5b is a side view thereof;

Fig. 6a is a plan view of another modified form of header, Fig. 6b being the side view thereof;

Figs. 7a and 7b are respectively a plan view and a side view of a stretcher;

Fig. 8a is an end view of a special header, Fig. 8b being the side view thereof;

Fig. 9a is a plan view of a further modified form

of header, Fig. 9b being the side view thereof; and Figs. 10a and 10b are respectively a plan view and a side view of a modified form of stretcher.

One of the most difficult conditions to provide for in the construction of a furnace wall is the effect of the violently fluctuating expansion and contraction strains in the hotter courses of brick on the inside lining of the wall, the firebrick being a relatively poor conductor of heat and the temperature drop through the wall normally being very steep. Thus, eight hours or more are required after a cold furnace is put into operation for the wall to heat up to the proper furnace temperature; conversely, the hot exposed surface face cools off at a much faster rate than the interior of the wall, when the furnace is shut down.

Since many plants operate for a part only of each day, with additional weakend shut downs, the expansion and contraction strains, and particularly in the furnace lining courses, are very severe and result in failure of the furnace walls due to mechanical failure of the inside courses of brick.

The vertical and horizontal expansion which periodically occurs in the hotter section of the wall produces a very marked tendency for the inside courses to bend or pull inwardly and so pull away from the cooler portion of the wall. The standard type of firebrick construction relies on the weight of the superimposed wall to hold the inside courses to the rest of the wall, it being standard practice to use a strong bond of overlapping headers through the wall so as to progressively transmit the weight of the superimposed wall to the inner lining. This type of construction causes the weight on the supporting headers to become progressively greater in the lower portions of the wall, where the highest temperature and the most violent fluctuations of temperature occur, with resultant violent expansion and contraction. The supporting headers normally project half their length into the hottest zone of the wall, and the projecting half is thus heated to a high temperature and is forced to expand upwardly before any material temperature and volume change has occurred in the cooler half, which is imbedded in the superimposed cooler section of the wall immediately above. When the effects of the temperature strains have snapped sufficient supporting headers, the bond between the inner and outer courses is broken, and the hot inner lining splits away from the cooler section of the wall.

Moreover, no suitable provision can be con-

veniently made with standard construction to relieve vertical expansion other than to leave the top of the wall clear. There is an additional disadvantage with standard constructions in that 5 the refractory qualities of firebrick which are exposed to high temperatures decrease with increase of the super-imposed load, wherefore the exposed brick in the lower part of the furnace wall are subjected to the most unfavorable conditions, because they are subjected to the maximum load, to the highest temperature, and to the greatest temperature range.

I have found it desirable to use a wall construction which more effectively meets these conditions, and thereby assures longer service and lower cost for repairs than it is possible to obtain with the use of standard brick, the construction being applicable to either solid or air cooled furnace walls of any desired thickness. To this end, 10 I provide special brick which has the same overall dimensions as standard firebrick, and occupies the same space in the wall, so that it may be laid up in the wall with a standard brick backing by usual brick laying methods.

15 Referring to the drawings, and particularly to Figs. 1 to 3, the furnace wall construction includes a plurality of separate panel sections 15, which are formed of special brick, the special brick being laid up with standard brick which 20 forms the outer wall portion 16. Each of these panels may independently expand both vertically and horizontally, the brick being so arranged as to bond each panel independently to the outer portion of the wall so as to be independently supported thereby.

25 Standard brick, as illustrated as 17 in Figs. 4a and 4b are used to lay up the outer portion of the wall, and the inner lining starts with a brick of the A type, indicated at 18 in Figs. 5a and 5b, 30 half of which lays up with the standard brick used in the outer portion of the wall. B headers, designated 19 in Figs. 6a and 6b, then overlap the inclined portions of the A headers, and C stretchers such as illustrated at 20 in Figs. 7a and 7b fit 35 or nest together with the A and B headers. There are many possible combinations in which these three bricks can be laid up together, an illustrative combination being shown in Fig. 2, the essential features of the construction residing 40 in the use of inclined joints instead of horizontal joints on the headers between the inside courses of brick on the furnace face. The joints on the furnace face of the wall may be changed at any point from horizontal to inclined and back 45 to horizontal by the use of standard feather edges, a special feather edge header D illustrated at 21 in Figs. 8a and 8b being preferred to make a firm base for starting the change from horizontal to inclined joints as shown in Fig. 2.

50 The above described construction locks the inner lining firmly to the rest of the wall by its own weight, and at the same time relieves the inner lining from the progressively increasing weight of the superimposed wall. This relief is accomplished by the overlapping of A and B headers 55 so that the weight of the superimposed inner lining is progressively transmitted through the inclined portion of the A header beneath, to the cooler outer part or section of the wall. Each 60 course of B headers, irrespective of its position in the wall, thus supports the superimposed load of a relatively small number of courses of stretchers. The exposed furnace face of the 65 wall is therefore divided into separate horizontal 70 panels, separated by expansion joints each self

75 supporting and each consisting of B headers and a small number of superimposed courses of C stretchers. Although any angle of incline found desirable may be used, the preferred angle is approximately 30°, more exactly 29° 3', so as to provide bricks in which the rise is in the ratio of the thickness of a standard firebrick to its width.

The projecting portions of the A and B headers are thus cantilevers which each support a 10 load uniformly distributed over its length, the maximum force acting vertically downward being exerted at the point of support and diminishing to zero at the furnace face of the wall. The load on each brick in the inner lining thus 15 progressively falls and is negligible at the hottest section nearest the face. Moreover, the weight on each successive brick is progressively reduced so that the top stretchers in any section on the exposed face support no load at all.

20 The above described construction has great advantages when compared with standard firebrick construction, as the load on the exposed face of the brick at the lower, hotter half is very much less, and depends on the small number of brick 25 in each panel. The inclined arrangement of the inner lining provides a gravity load on the inner lining which tends to press the inner lining towards the outer wall portion, whereby a breaking of headers does not result in a separation of 30 the inner lining, and instead will cause the inner lining to settle on the panel below and to hug the outer wall portion with a force dependent on its weight. The relief of the super-imposed weight on the hot lining and the locking of the 35 inner lining firmly to the rest of the wall permits more effective provision for expansion than is possible with standard brick construction, longitudinal expansion being preferably provided for 40 by open vertical joints which are staggered or broken across the wall, and located at regular intervals as required as illustrated in Fig. 1. Vertical expansion is provided for by leaving an open horizontal joint beneath spaced courses of B headers, as indicated in Figs. 1 and 2, the described 45 arrangement in effect dividing the entire inner face of the wall into comparatively small rectangular panels which are self supported and are free to move both vertically and horizontally 50 as they expand and contract, independently of the adjacent panels.

55 The provision of separate panels facilitates the making of necessary replacements, as any panels, including all of the supporting B headers, can be removed and replaced with a minimum of disturbance to the rest of the wall. The replacements require a minimum of new material as compared with those necessary to replace a bonded standard firebrick wall, which uses more header than stretcher courses on the furnace face. Instead of replacing all the headers, as is necessary when the face of a standard furnace wall is replaced, the novel construction only requires a replacement of a large number of stretchers and a relatively small number of headers, thus lowering the cost of repairs.

60 The above described construction may also be applied to air cooled walls which have lanes or channels behind the hot face through which air is passed to cool the refractories. The thickness of the wall in this type of construction must be reduced to a relatively thin section in order to effectively lower the temperature in the heated portion. This requires special steel supports for 65 standard type walls, as a relatively thin section 70

is too weak to carry the superimposed weight; moreover, the supporting steel work, and especially the hangers holding the inner lining, must be protected from high temperatures, thus requiring thick refractory shapes to protect the hangers. Since the novel construction heretofore described divides the inner lining into self supporting sections which do not support substantial weight, the novel construction may be readily adapted to air cooled walls, the exposed face being thin enough to effectively reduce the temperature on the hot face without requiring special supporting steel work and vulnerable metal hangers.

15 Referring to Fig. 3, the inner lining is made up of special headers E, as shown at 22 in Figs. 9a and 9b, and superimposed stretchers F, designated 23 in Figs. 10a and 10b, which are joined together as illustrated to provide air passages 20 or channels 24, the resulting inner lining being thin enough to effectively reduce the temperature in the hot part of the wall and thick enough to be mechanically strong, in view of the reduced weight supported by each header. It is preferred 25 to use double A headers, as disclosed in Fig. 3, to additionally support the inner lining, and to form the headers and stretchers with notches as indicated at 25 and 26 so as to provide a secure lock between the adjacent stretchers and 30 headers.

The above described construction is particularly suitable for air cooling, as the E header which carries the stretcher load is very effectively air cooled. The brick in the exposed inner lining is 35 also effectively air cooled, except the F stretcher at the top; this stretcher, however, carries no superimposed load.

While I have described a specific constructional embodiment of my invention, it is obvious 40 that any change in size and shape of the firebrick and in their arrangement, may be made to suit the requirements for different furnace installations without departing from the spirit and the scope of the invention as defined in the appended claims.

I claim:

1. In a furnace wall construction, an outer section of standard brick, and an inner lining, said inner lining having a plurality of headers bonded to said outer section, said headers having rhomboidal portions extending from said outer section, rhomboidal headers on said first headers and projecting therefrom, and rhomboidal stretchers on said headers.

55 2. In a furnace wall construction, an outer section of standard brick, and an inner lining, said inner lining having a plurality of headers bonded to said outer section, said headers having rhomboidal portions extending from said outer section, rhomboidal headers on said first headers and projecting therefrom, and rhomboidal stretchers on said headers, the inner lining comprising horizontal sections formed of sets of stretchers mounted on vertically spaced header courses, the sections having horizontal expansion joints therebetween.

3. In a furnace wall construction, an outer section of standard brick, and an inner lining, 70 said inner lining having a plurality of headers bonded to said outer section, said headers having rhomboidal portions extending from said outer section, rhomboidal headers on said first headers and projecting therefrom, and rhomboidal stretchers on said headers, the sections being

divided into panels having vertical expansion joints therebetween.

4. In a furnace wall construction, an outer section of standard brick, and an inner lining, said inner lining having a plurality of headers bonded to said outer section, said headers having rhomboidal portions extending from said outer section, rhomboidal headers on said first headers and projecting therefrom, and rhomboidal stretchers on said second headers spaced from 10 said outer section, whereby air passageways are provided between said lining and said outer section.

5. In a furnace wall construction, an outer section of standard brick, and an inner lining, 15 said inner lining having a plurality of headers bonded to said outer section, said headers having rhomboidal portions extending from said outer section, rhomboidal headers on said first headers and projecting therefrom, and rhomboidal stretchers on said second headers spaced from 20 said outer section, whereby air passageways are provided between said lining and said outer section, the inner lining comprising horizontal sections formed of sets of stretchers mounted on 25 vertically spaced header courses, the sections having horizontal expansion joints therebetween.

6. In a furnace wall construction, an outer section of standard brick, and an inner lining, 30 said inner lining having a plurality of headers bonded to said outer section, said headers having rhomboidal portions extending from said outer section, rhomboidal headers on said first headers and projecting therefrom, and rhomboidal 35 stretchers on said second headers spaced from said outer section, whereby air passageways are provided between said lining and said outer section, the sections being divided into panels having vertical expansion joints therebetween.

7. In a furnace wall construction, an outer section of standard brick, and an inner lining, said inner lining having a plurality of headers bonded to said outer section, said headers having rhomboidal portions extending from said outer section, rhomboidal headers on said first headers and projecting therefrom, and rhomboidal 45 stretchers on said second headers spaced from said outer section, whereby air passageways are provided between said lining and said outer section, said second headers and said stretchers having cooperating locking shoulders.

8. In a furnace wall construction, an outer section of standard brick, and an inner lining, said inner lining having a plurality of headers bonded to said outer section, said headers having rhomboidal portions extending from said outer section, rhomboidal headers on said first headers and projecting therefrom, and rhomboidal stretchers on said second headers spaced from 55 said outer section, whereby air passageways are provided between said lining and said outer section, the inner lining comprising horizontal sections formed of sets of stretchers mounted on vertically spaced header courses, the sections 60 having horizontal expansion joints therebetween, said second headers and said stretchers having cooperating locking shoulders.

9. In a furnace wall construction, an outer section of standard brick, and an inner lining, 70 said inner lining having a plurality of headers bonded to said outer section, said headers having rhomboidal portions extending from said outer section, rhomboidal headers on said first headers and projecting therefrom, and rhom- 75

boidal stretchers on said second headers spaced from said outer section, whereby air passageways are provided between said lining and said outer section, the sections being divided into panels having vertical expansion joints therebetween, said second headers and said stretchers having cooperating locking shoulders.

10. In a furnace wall construction, an outer section, and an inner lining, said inner lining comprising a plurality of headers bonded to said outer section and having portions upwardly inclined with respect thereto, a plurality of headers each mounted on the inclined portion of one of said first-named headers and having the inner ends thereof locked to the outer section, and stretchers similarly inclined and mounted on said headers.

11. In a furnace wall construction, an outer section, and an inner lining, said inner lining comprising a plurality of headers bonded to said outer section and having portions upwardly inclined with respect thereto, a plurality of headers each mounted on the inclined portion of one of said first-named headers and having the inner ends thereof locked to the outer section, and stretchers similarly inclined and mounted on said headers.

12. In a furnace wall construction, an outer section, and an inner lining, said inner lining comprising a plurality of headers bonded to said outer section and having portions upwardly inclined with respect thereto, a plurality of headers each mounted on the inclined portion of one of said first-named headers and having the inner ends thereof locked to the outer section, and stretchers similarly inclined and mounted on said headers, the inner lining comprising horizontal sections formed of sets of stretchers mounted on vertically spaced header courses, the sections having horizontal expansion joints therebetween.

13. In a furnace wall construction, an outer section, and an inner lining, said inner lining comprising a plurality of headers bonded to said outer section and having portions upwardly inclined with respect thereto, a plurality of headers each mounted on the inclined portion of one of said first-named headers and having the inner ends thereof locked to the outer section, and stretchers similarly inclined and mounted on said headers, the inner lining comprising horizontal sections formed of sets of stretchers mounted on vertically spaced header courses, the sections having horizontal expansion joints therebetween.

14. In a furnace wall construction, an outer section, and an inner lining, said inner lining comprising a plurality of headers bonded to said outer section and having portions upwardly inclined with respect thereto, a plurality of headers each mounted on the inclined portion of one of said first-named headers and having the inner ends thereof locked to the outer section, and stretchers similarly inclined and mounted on said headers, the inner lining comprising vertical sections formed of sets of stretchers mounted on vertically spaced header courses, the sections having horizontal expansion joints therebetween, the sections being divided into panels having vertical expansion joints therebetween.

WILLIAM A. WAITE.
